COMBINED TABLE AND MULTIPLE SEAT UNIT
FOR STUDENT INSTRUCTION

Richard C. Bue and Julian Gutierrez, Minneapolis, Minn.,
assignors to Sico Incorporated, Minneapolis, Minn., a
corporation of Minnesota

Filed July 5, 1966, Ser. No. 2,940

Term of patent 14 years

(Cl. D33—11)

FIG. 1

FIG. 2

FIG. 3

FIG. 4

FIG. 1 is a perspective view of a combined table and multiple seat unit for student instruction showing our new design;

FIG. 2 is a rear elevation thereof;

FIG. 3 is a bottom plan view thereof; and

FIG. 4 is a side elevational view as seen from the right side thereof, the left side being a mirror image thereof.

We claim:

The ornamental design for a combined table and multiple seat unit for student instruction, as shown and described.
